(57) **CLAIM**

The ornamental design for a butterfly orthopedic coccyx cushion, as shown and described.

DESCRIPTION

FIG. 1 is a top perspective view of a butterfly orthopedic coccyx cushion, showing my new design;

FIG. 2 is a front view of the butterfly orthopedic coccyx cushion;

FIG. 3 is a rear view of the butterfly orthopedic coccyx cushion;

FIG. 4 is another top perspective view of the butterfly orthopedic coccyx cushion;

FIG. 5 is a left side view of the butterfly orthopedic coccyx cushion;

FIG. 6 is a right side view of the butterfly orthopedic coccyx cushion; and,

FIG. 7 is a top perspective view of the butterfly orthopedic coccyx cushion, shown in a state of use. The broken lines shown in FIG. 7 are for the purpose of illustrating environmental structure, and form no part of the claimed design.

1 Claim, 7 Drawing Sheets
